UNITED STATES PATENT OFFICE.

WILLIAM F. HELMOND, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING MACHINE.

Application filed February 25, 1919. Serial No. 279,081.

To all whom it may concern:

Be it known that I, WILLIAM F. HELMOND, a citizen of the United States, residing in Hartford, in the county of Hartford and State of Connecticut, have invented certain new and useful Improvements in Typewriting Machines, of which the following is a specification.

This invention relates to typewriters, and especially to the releasable means for locking the keys as soon as a line has been written; and an object of the invention is to provide an improved line-lock release mechanism, whereby the efficiency of the machine as a whole is increased.

In the Underwood machine, a carriage lug depresses a cam which operates a pendent arm. This arm moves the usual key-locking bar into interfering position relatively to the key levers. A button is provided which passes horizontally through a hole in the left side of the typewriter frame, and engages and moves the pendent arm, to effect the release of the keys. With this construction, the operative is compelled to take his hand from the region of the keyboard in order to release the keys. This is a time-consuming and awkward movement.

According to the present invention, a depressible key is located in the keyboard, preferably at the left of one of the usual lower banks of keys, for effecting the release of the locked type keys, and said pendent arm is moved outwardly instead of inwardly to effect key release. This may be accomplished by providing an inwardly-directed pin on the pendent arm to engage the upstanding arm which moves the key-locking bar, and by providing a cam on the pendent arm for engagement by a bent-over portion of the key-release lever. This construction also permits of a longer key-locking bar than has been heretofore feasible.

Other features and advantages will hereinafter appear.

In the accompanying drawings,

Figure 1 represents a side elevation of an Underwood typewriter having my improvement embodied therein.

Figure 2 is a perspective view looking from the right.

Figure 3 is an elevational view of parts of the mechanism as seen from the right side

of the machine, said view showing the keys 55 locked.

Figure 4 is a perspective view looking from the left and showing the parts in the position they assume at the moment of unlocking of the keys.

The typewriting machine may comprise the usual keyboard having keys 1, said keys comprising key-levers 2, connected through bell-crank 3, to type bars 4 having types 5 thereon, as indicated in Figure 1. The depression of any key swings a type bar about its pivot upwardly and rearwardly to cause a type to strike against the front face of a platen 6, supported in a carriage 7. The carriage may be fed a letter-space at a time 70 on the depression of each key through the usual escapement mechanism 8, comprising a fixed and a movable dog which alternately engage with the escapement wheel 9, mounted upon a stud shaft extending into 75 the typewriter frame. Adjacent the escapement wheel 9 and also mounted on the stud shaft is a pinion 10 which engages a rack 11 mounted on the typewriter carriage. The usual spring (not shown) tends to move the 80 carriage in one direction when permitted to do so by action of the escapement dogs.

The escapement dogs are operated by means of a frame 12 having a bar 13 universal to all of the type bars and actuated 85 by each type bar through the medium of a cam formation 14 as each type bar approaches the end of its stroke.

The key-locking mechanism includes a shaft 15 pivoted underneath the typewriter 90 key levers and having adjacent each end thereof upstanding arms 16 and 17 rigidly secured thereto, which arms carry a key-locking bar 18, which bar is adapted to move under rearwardly-extending lugs 19 95 carried by the key levers, when the shaft 15 is rocked.

The shaft 15, together with the arms 16 and 17, and the lock bar 18, are urged to position wherein the bar 18 unlocks the 100 keys, by a spring 20 coiled about the shaft 15 and fastened to a pin 21 projecting from the arm 17, the other end of the spring being attached to some stationary part, as, for instance, a pin 22. Upstanding from the shaft 15 and to the left and adjacent to the arm 17 is another arm 23 also rigid with the shaft 15, which arm is adapted to be

engaged and moved to rock the shaft 15 against the tension of the spring 20, whereby the locking bar 18 is moved to position to lock the keys.

It is desirable that the key-locking take place at the end of a line of writing, and to this end the carriage of the typewriter has a projecting arm 24 which carries a cam member 25, which member is adapted to contact with a cam 26 which engages a yoke member 27 pivoted for rocking movement on a shaft 28 extending between the side frame members of the typewriter. The cam 26 forms part of an adjustable member 29 which is movable along the shaft 28 to determine the position in the line of writing at which the key-locking takes place. Connected to the yoke member 27, just inside of the typewriter frame, as shown in Figures 1, 3 and 4, is a depending arm 30, which carries at its lower end a pawl 31 which is adapted to engage and rock the arm 23, above described. The pawl 31 is pivoted at the lower extremity of the arm 30 and has a lip 32 which is bent over the back edge of the arm 30, so that the pawl may rock in one direction but moves as though rigid with the arm 30 when said arm is moved in the other direction. This rocking movement of the pawl is desirable because not only does the pawl serve as a means for actuating the means for locking the keys, but also as a means for ringing a signal bell 33, which is provided with the usual hammer 34, the hammer arm being formed of a pivoted lever having a cam end 35 against which the pawl 31 wipes as the arm 30 moves in the direction of the arrow, Figures 1 and 4. When so moving, the lip 32 prevents the pawl from rocking, so that the hammer lever 35 is first depressed and then releases so as to ring the bell. On its return movement, however, the pawl rocks to permit clearance. During the forward movement of the arm 30, the pawl 31 also causes a pin 36 (see Figure 3) extending inwardly or from the right side thereof to engage the arm 23, as indicated in Figure 3, thereby rocking the arm 23 and consequently the shaft 15 and key-locking bar 18.

Contrary to prior instructions, the arm 30 is adapted to be moved outwardly or to the left so as to remove the pin 36 on the pawl 31 from behind the arm 23, and so as to permit the spring 20 to move the locking bar 18 to normal position to release the keys. In order to move the arm 30 outwardly, it is provided with a bent-over cam member 37 which is adapted to be engaged by a bent-over projection 38 carried by a lock-release key comprising a key lever 39, having a finger-piece 40. The key lever 39 is mounted along with the rest of the typewriter key levers and its finger-piece 40 is for convenience arranged in one of the lower rows or

banks of keys, preferably at the left-hand end of said row. The lever 39 may be pivotally mounted on the shaft which supports the bell-cranks 3, said shaft being extended, if necessary, for such purpose, and a spring 39' may be provided to return said lever to normal position after each depression thereof.

When the carriage of the typewriter reaches such a position in the line of writing that the cam member 25 contacts the cam 26, the yoke 27 is rocked and the member 30 moved to the position shown in Figure 3, with the cam 37 under the projecting lug 38. When the key 40 is depressed, the lug 38 cams the member 30 outwardly and engages the pin 36 on the pawl 31 from the arm 23. The spring 20 then returns the locking bar 18 to normal position and the keys are free. By having the key-release mechanism in the keyboard along with the other keys, the operative does not need to move his or her hand from the position over the keyboard, and time is thereby saved. Furthermore, by reason of the fact that the member 30 moves outwardly instead of inwardly, as has been the custom heretofore, there is more room available at the left-hand side of the machine, so that the locking bar 18 may be made longer.

Variations may be resorted to within the scope of the invention, and portions of the improvements may be used without others.

Having thus described my invention, I claim:

1. In a typewriting machine, the combination with a keyboard including a plurality of keys, of locking means to lock said keys against operation at the end of a line of writing, said locking means having an operating arm located adjacent one end of the typewriter frame, a movably mounted controller bar for said locking means, said bar having a part capable of being brought into contact with said operating arm so as to move the same and render said locking means effective, a lock-release key in said keyboard, and means rendered effective on depression of said key for moving the contacting portion of said bar toward the adjacent end of said typewriter frame, thereby separating it from said operating arm and permitting said locking means to release said keys.

2. In a typewriting machine, the combination with a keyboard including a plurality of keys, of means for locking said keys at the end of a line of writing, a pendent arm extending from the upper part of the typewriter frame and controlling said locking means, said arm having a bent-over lip forming a cam, and a key in the keyboard having a bent-over lug formed for engagement with said cam lip to move said pendent arm to release said keys.

3. In a typewriting machine, the combination with a plurality of keys, of locking means for said keys, including a rock shaft, a locking bar moved by said shaft to lock the keys, a spring to return said shaft and bar, an arm carried by said shaft, an arm pendent from the upper part of the typewriter frame having a pin on the inner face thereof, to engage said first-mentioned arm and thereby move said locking bar to lock said keys, and a key-release including means to move said pendent arm outwardly so as to withdraw said pin from engagement with the arm carried by said rock shaft, to permit said spring to move said locking 15 bar to position to release said keys.

WILLIAM F. HELMOND.
